GRINDING DEVICE FOR KNIVES AND THE LIKE

Henry H. Townshend, New Haven, Conn., assignor to J. T. Henry Manufacturing Co., Inc., Hamden, Conn., a corporation of Connecticut

Application November 5, 1953, Serial No. 390,367

3 Claims. (Cl. 51—102)

This invention relates to knife sharpeners, and more particularly to a simply constructed device of relatively light weight which comprises a grinding wheel driven by water power and provided with means by which it may be connected to the ordinary domestic water outlet or faucet.

It is contemplated by the present invention to provide a relatively simple and inexpensive device for use by the average householder to sharpen kitchen and other knives. Devices for this purpose have been constructed which are driven by means of an electrical motor, but these devices are relatively expensive, principally on account of the expense of the motor, and are also of relatively heavy weight.

The device of the present application comprises a relatively simple structure which will be inexpensive to manufacture and which will also be of relatively light weight so that it may, if desired, be supported upon a suitable surface or may be held in the hand during the sharpening operation. As illustrated, it comprises a housing or casing within which is rotatably mounted a shaft having a turbine or water wheel upon the upper end thereof and a grinding stone upon the lower end thereof. Provisions are made for supplying water to the turbine from a source of supply such as a city water supply, for example, through a tangentially directed nozzle so that a stream of water under pressure will be directed against the blades of the turbine to rotate the same, and in this manner rotate the grinding stone.

Also, as illustrated, the casing or housing is of cylindrical shape, and a slot is provided at one side of the casing so that a knife blade may be inserted into this slot with its edge in contact with the peripheral surface of the grinding wheel so that the knife may be drawn across this surface while the wheel is being rotated and the edge of the knife sharpened.

Moreover, provision is made for discharge of the water from the turbine downwardly through the casing so that the water passes over the grinding wheel and serves as a coolant as well as washing away emery dust so there is no danger of this dust collecting in the bearings of the device.

One object of the present invention is to provide a grinding device for knife sharpening or the like which will be relatively inexpensive and of light weight and efficient in operation.

A still further object of the invention is the provision of a grinding wheel for knives or the like operated by water power, the grinding wheel being mounted below a water-operated turbine, and the water from the turbine directed downwardly over the grinding wheel.

A still further object of the invention is the provision of a knife sharpener operated by water power and of relatively light weight so that it may be held in the hand, if desired, during use, the knife sharpener comprising a casing having therein a water-operated turbine wheel secured at the upper end of a shaft rotatably mounted in the casing, the shaft carrying a grinding wheel at its

2

lower end, and provision for permitting discharge of the water from the turbine downwardly over the grinding wheel to cool the same and wash loosened abrasive particles therefrom.

To these and other ends the invention consists in the novel features and combinations of parts to be hereinafter described and claimed.

In the accompanying drawings:

Fig. 1 is a side elevational view of a knife sharpener embodying my invention;

Fig. 2 is a front elevational view thereof;

Fig. 3 is a sectional view on line 3—3 of Fig. 2; and

Fig. 4 is a sectional view on line 4—4 of Fig. 3.

To illustrate a preferred embodiment of the invention, there is shown in the drawings a knife sharpener comprising a casing 10 which, as shown, is of substantially cylindrical shape, the casing being open at its upper and lower ends. Midway between the upper and lower ends the casing is provided with a web 11 having openings 12 therethrough to provide communication between the upper and lower portions of the casing for the exhaust flow of water therethrough.

The web 11 provides centrally of the casing an axially disposed bearing member 13 within which is mounted a bearing sleeve 14 having an upper enlarged end 15 resting upon the bearing 13. The sleeve 14 may be held in place by a nut 16 threaded upon the lower end thereof which protrudes from the bearing member 13.

Rotatably mounted within the bearing 14 is a shaft 17, this shaft being somewhat reduced in size at its intermediate portion, as shown at 18, so as to reduce the bearing surface between this shaft and the sleeve 14.

The shaft is provided with an annular shoulder 19 above the portion 15 of the bearing sleeve, and depending from this shoulder is an annular flange 20 which is rotatably received in an annular recess 21 in the enlarged portion 15 of the sleeve 14. Thus the shaft 17 is rotatably mounted in the bearing sleeve 14 with a minimum amount of friction.

Rigidly secured to the upper end of the shaft 17 is a turbine or water wheel having a hub 23 which receives the shaft and which may be held upon the shaft by the nut 24. This turbine comprises a body portion 25 from which depend vanes 26, curved, as shown in Fig. 4, so that a jet of water may be directed upon them and effect rotation of the wheel.

At the lower end of the casing the shaft 17 is provided with a reduced polygonal end 27 upon which is fixed a grinding wheel 28, this wheel being clamped upon collars 29 and 30 threaded upon the reduced end 27 of the rotatable shaft. It may here be noted that the grinding wheel is mounted below the turbine or on the same side thereof as the vanes 26, so that after a stream of water has been directed upon the vanes, it will pass downwardly through the openings 12 in the supporting web 11 and be discharged over the grinding wheel 28 so as to provide a coolant for the wheel as well as to wash the emery dust or other abrasive particles therefrom.

The casing 10 is provided with a slot 32 of planar form, shown more especially in Figs. 2 and 3, this slot being provided in an upwardly inclined direction so that a knife blade, shown in dotted lines at 33 in Fig. 3, may be inserted through the slot and its edge drawn across the grinding wheel in contact with the periphery thereof so as to be sharpened. It will be understood that the knife may be drawn across the wheel first in one direction and then in the other in order to sharpen both sides thereof.

At the upper end of the casing adjacent the turbine wheel there is provided a tangentially disposed neck or inlet member 34 to which may be secured the inlet or injecting nozzle 35, the forward end of this nozzle extending into the neck 34 in close proximity to the vanes

26 so as to direct a stream of water thereon. This nozzle may be connected to the usual household water faucet by a flexible tube or the like 36.

It will be apparent that with the above construction I have provided a knife sharpener of very simple construction and one of light weight which may, if desired, be held in the hand during use. Moreover, it may be used even by those ordinarily unskilled in knife sharpening operations in that the slot 32 is so provided as to guide the knife blade into proper contact with the grinding wheel. In addition, the discharge of the water from the lower side of the turbine wheel downwardly through the casing over the grinding wheel not only provides a convenient discharge outlet for the water employed, but also employs this water as a coolant for the wheel and also as a means to remove emery dust and other particles from the grinding wheel.

While I have shown and described a preferred embodiment of my invention, it will be understood that it is not to be limited to all of the details shown, but is capable of modification and variation within the spirit of the invention and within the scope of the claims.

What I claim is:

1. A knife sharpener comprising a substantially cylindrical casing open at both ends, a web provided at an intermediate portion of the casing, a bearing supported by said web, a shaft rotatably mounted in said bearing, a turbine wheel secured to the upper end of said shaft, said turbine wheel having a body portion serving as a closure member for the upper end of the casing, and blades carried by, and depending downwardly from, the body member, a grinding wheel within said casing and secured to the lower end of said shaft below said web, means for directing a jet of fluid against the blades of said turbine wheel, said web being provided with openings to permit discharge of the fluid over the grinding wheel, and the wall of the casing being provided with a slot extending therethrough adjacent the grinding wheel and inclined to the vertical to permit insertion of a knife blade therethrough into contact with the periphery of the grinding wheel.

2. A knife sharpener comprising a substantially cylindrical casing open at both ends, a web provided at an intermediate portion of the casing, a bearing supported by said web, a shaft rotatably mounted in said bearing,

a turbine wheel secured to the upper end of said shaft, said turbine wheel having a body portion serving as a closure member for the upper end of the casing, and blades secured at the lower surface of, and depending downwardly from, the body member, a grinding wheel within said casing and secured to the lower end of said shaft below said web, an inlet member arranged tangentially of the casing adjacent the turbine wheel, a nozzle carried by said inlet member to direct a jet of fluid against the blades of the wheel, and said web being provided with openings to permit discharge of the fluid from said turbine wheel downwardly over the grinding wheel.

3. A knife sharpener comprising a substantially cylindrical casing open at both ends, a web provided at an intermediate portion of the casing, a bearing supported by said web, a shaft rotatably mounted in said bearing, a turbine wheel secured to the upper end of said shaft, said turbine wheel having a body portion serving as a closure member for the upper end of the casing, and blades depending downwardly from the body member, a grinding wheel within said casing and secured to the lower end of said shaft below said web, an inlet member arranged tangentially of the casing adjacent the turbine wheel, a nozzle carried by said inlet member to direct a jet of fluid against the blades of the wheel, said web being provided with openings to permit discharge of the fluid from said turbine wheel downwardly over the grinding wheel, and the wall of said casing being provided with a slot of planar form extending therethrough adjacent the grinding wheel and inclined to the vertical whereby the walls of said slot serve to guide a knife blade into edge contact with the periphery of the grinding wheel.
